US00D918861S

(12) **United States Design Patent** (10) **Patent No.:** **US D918,861 S**
Chen (45) **Date of Patent:** **** May 11, 2021**

(54) **COMBINED SPEAKER AND MICROPHONE**

(71) Applicant: **Ching-Wen Chen**, Taipei (TW)

(72) Inventor: **Ching-Wen Chen**, Taipei (TW)

(**) Term: **15 Years**

(21) Appl. No.: **29/716,056**

(22) Filed: **Dec. 6, 2019**

(51) LOC (13) Cl. **14-01**

(52) U.S. Cl.

USPC **D14/204**; D14/206

(58) **Field of Classification Search**

USPC D14/204-216, 155-159, 160-173, 187,
D14/188, 203.1-203.8, 217-222, 225-229

(57) **CLAIM**

The ornamental design for a combined speaker and microphone, as shown and described.

DESCRIPTION

FIG. 1 is a top perspective view of a combined speaker and microphone showing my new design;

FIG. 2 is a front view thereof;

FIG. 3 is a rear view thereof;

FIG. 4 is a left elevational side view thereof;

FIG. 5 is a right elevational side view thereof;

FIG. 6 is a top plan view thereof;

FIG. 7 is a bottom plan view thereof; and,

FIG. 8 is a rear perspective view.

The broken lines depict portions of the combined speaker and microphone that form no part of the claimed design.

1 Claim, 7 Drawing Sheets
